UNITED STATES PATENT OFFICE

131,081

DESIGN FOR A BOTTLE

Frank W. Britt, Jackson Heights, N. Y., assignor to Conti Products Corporation, Brooklyn, N. Y.

Application November 15, 1941, Serial No. 104,167

Term of patent 3½ years

To all whom it may concern:

Be it known that I, Frank W. Britt, a citizen of the United States, residing at Jackson Heights, Long Island, county of Queens, and State of New York, have invented a new, original, and ornamental Design for a Bottle, of which the following is a specification, reference being had to the accompanying drawing, forming a part thereof.

In the drawing, Fig. 1 is a perspective view of a bottle, showing my new design; Fig. 2 is a sectional view thereof taken on the line 2—2 of Fig. 1.

I claim:

The ornamental design for a bottle, as shown.

FRANK W. BRITT.
